EDWARD B. CRAFT AND AMOS F. DIXON, OF NEW YORK, N. Y., ASSIGNORS TO WESTERN ELECTRIC COMPANY, OF CHICAGO, ILLINOIS, A CORPORATION OF ILLINOIS.

SELECTOR MECHANISM.

1,081,368.

Specification of Letters Patent. Patented Dec. 16, 1913.

Application filed January 11, 1908. Serial No. 410,320.

To all whom it may concern:

Be it known that we, EDWARD B. CRAFT and AMOS F. DIXON, citizens of the United States, residing at New York, in the county 5 of New York and State of New York, have invented a certain new and useful Improvement in Selector Mechanism, of which the following is a full, clear, concise, and exact description.

10 This invention relates to a selector mechanism particularly adapted for use in so-called automatic or semi-automatic telephone exchange systems.

The invention has especial reference to a 15 type of selector in which the electromagnets which respond to the electrical selecting impulses or currents instead of being required themselves to perform the work of advancing the movable switch member of the selector, act merely to adjust light and easily moved controller parts which set a stop to determine the limit of travel of the switch member, power being then applied, as by a magnetic clutch, to carry such switch member 20 to the point so selected.

The principal feature of this invention lies in the provision of two or more selectively-adjustable controller parts which by their relative positions, determine the setting 30 of the stop, a coöperating member being arranged to be governed by the combination thus set up, to limit the operation of the power-driven switch. More specifically, it is contemplated that these controller parts may 35 have scales thereon with differently-spaced divisions, like those of a vernier, the first point of coincidence of the scales being the determining factor in the setting of the stop. The two controller parts may be, for example, 40 rotatably-adjustable disks arranged side by side, said disks having notches on their edges spaced apart different distances on the different disks; and a pawl or rider may be arranged to travel around the edges of these 45 disks according as the movable switch member of the selector is advanced over its terminals. The pawl will be adapted to drop into the notches of the disks at the first point of coincidence thereof, and in so doing will 50 actuate a stop-switch to throw off the clutch or otherwise arrest the advance of the switch member. The stop-setting or controller parts being light and easily moved require little mechanical work to be done by the 55 magnets which respond to the selecting im-

pulses; and the setting of the stop according to their relative positions, on the principle of a vernier or combination-lock, makes it possible to determine a very wide range of travel of the switch by exceedingly slight 60 selecting movements or adjustments of these parts.

In constructing a selector mechanism upon the plan above outlined, we have further made various detail improvements which 65 can best be understood by reference to the accompanying drawings illustrating one of many forms or specific embodiments of our invention.

Figure 1 is a diagram illustrating the 70 principal operating parts of a selector switch, this diagram not being intended to show actual shapes or proportions of the parts, but only to indicate in a schematic way the various elements of a complete 75 "final selector" or "connector", and, in general, their relations to each other; Fig. 2 is a side view of the operating mechanism, the side of the supporting frame being removed; Fig. 3 is a front view thereof; Fig. 80 4 is a sectional view, the section being taken on the line of the central shaft; Fig. 5 is a detail view of the stepping and holding mechanism for the vernier controller-disks; Fig. 6 is an edge or front view of the parts 85 shown in Fig. 5; Fig. 7 is a detail view of the two stepping pawls carried by the armature lever of the stepping magnet; Fig. 8 is a detail perspective view of the two holding pawls for the adjusting-ratchets of the vernier controller-disks; Fig. 9 is a detail view 90 showing the parts which directly actuate the stop-switch that opens the circuits of the magnetic clutch; Fig. 9^a is a detail edge view of the clutch release switch springs; Fig. 10 95 is a detail view of the main holding-ratchet; and Figs. 11 and 12 are detail views of the vernier controller-disks.

Like parts are designated by similar characters of reference throughout the drawings. 100

The selector-switch shown is of a type wherein the movable switch member consists of a vertical slide-rod 50 carrying brushes 51, 52, 53 which are adapted to travel over and make contact with stationary line terminals 61, 62, 63, these line terminals being mounted for example, in a panel terminal-board. The brush carrier rod 50 is hung by a flexible steel ribbon 54 from the carrier sheave 71 of the operating 110

or "elevator" mechanism. By a rotary movement of the sheave, the brush carrier rod may be lifted to bring its brushes into contact with any desired set of stationary 5 terminals in their path.

The operating shaft 77 which carries the switch-moving sheave 71 is arranged to be rotated under control of a clutch magnet 70, by a power-shaft 72, to cause the brush-carrier 50 to advance its brushes to the point predetermined by the electromagnetic stop-setting mechanism which responds to the selecting impulses. The clutch members, consisting of friction plates 80, 81, (Fig. 4) 10 one of which is mounted upon the power-shaft 72, and the other upon a tubular operating shaft 77 carrying the sheave 71, are adapted to be drawn into engagement by the clutch magnet 70 acting on plate 81, 15 which is of iron. When said clutch magnet is excited, the carrier sheave will be rotated and the contact brushes advanced to the predetermined stopping point by power applied through said clutch members. 20 25 The stop setting mechanism, as shown in Figs. 1, 2, 5, and 6, comprises two vernier controller disks 73, 74, mounted side by side, said disks having peripheral notches adapted to be engaged by a pawl 75 which 30 is carried forward around the edges of said disks as the brush carrier moves from its zero position. This pawl 75 is carried by a disk 76 which is mounted upon the tubular shaft 77 of the carrier pulley 71 so 35 as to rotate therewith. Said disk 76 is provided with ratchet teeth to be engaged by a retaining pawl 89 adapted to be brought into service by the holding magnet 91. Side by side with the disks 73, 74 is a third disk 40 45 50 55 60 65 70 75 80 85 90 95 100 105 110 115 120 125 78 having notches around its edge so spaced that the travel of the pawl 75 from one of these notches to the next will correspond to a movement of the selector brushes from one set of stationary terminals to the next. The pawl 75 is normally held out of engagement with the notches of disk 78 by the disks 73, 74 upon which it rides; but when it reaches a point at which the notches of said disks 73, 74 coincide, it falls in, engages the corresponding notch of disk 78 and slightly rotates said disk. This slight movement of disk 78 is caused to actuate a set of switch springs 79 by which the circuit of the clutch magnet 70 may be opened. As shown in Fig. 9, the disk 78 has a lug 101 which projects between two adjustable limiting-stops 102, 103 between which it is permitted a slight movement. The actuating member for the stop-switch springs 79 is a bell-crank lever 115 one arm whereof actuates said springs while the other end projects into the path of the lug 101 on the disk 78. A spring 105 causes the bell crank lever normally to push the lug 101

backward against its rearward limiting stop.

The ratchet disk 76 carrying the pawl 75 is adapted to be held by the pawl 89 (brought into service when holding magnet 91 is excited) so that when the units disk 78 has been moved by pawl 75 sufficiently to actuate the clutch-release-spring-springs 79, said disk 78 is retained in such advanced position by the pawl 75, whether the clutch is on or not. But if under such circumstances the vernier disk 73 is given another advance step to throw the notches under pawl 75 out of coincidence, the pawl will thereby be raised out of engagement with the teeth of disk 78, permitting the latter to return to normal position under the influence of spring 105, and to restore the contact springs 79 to normal.

The point at which the notches of disks 73 and 74 will coincide, and consequently the stopping point of the brush carrier, is determined by the relative positions of said disks, which may be adjusted by means of electromagnetic step-by-step mechanism responsive to the selecting impulses. In the selector shown, the notches of disk 74 are spaced apart a distance corresponding to ten notches on the disk 78, which form, so to speak, a units scale. The notches of disk 73, on the other hand, are spaced apart a distance corresponding to only nine notches or divisions of said units disk 78. In the mechanism shown, the disks 73 and 74 normally rest so that a single independent step of disk 73 and a further step of both disks 73 and 74 together will bring the notches of all three disks into coincidence at zero, or a point corresponding to the first stationary terminal No. 0 on the selector. In the operation of the system in which this selector is particularly adapted to be used, the vernier disk 73 is always intended to take at least one independent step, which would set the point of coincidence one notch back from zero. If then the disk 73 is advanced an additional step equal to one space on the units scale, the first point at which the scales 73 and 74 coincide will be opposite the ninth notch of the units scale. Similarly, an advance of disk 73 through two additional steps from normal making three steps in all will throw the point of coincidence to the nineteenth notch of the units scale, and so on, each unit of advance of the vernier disk 73 throwing the point of coincidence a distance of ten units ahead. If it is desired to set up a coincidence at an intermediate point, between any given tens divisions and the next, that is accomplished by first advancing the vernier disk 73 a number of units steps sufficient to reach the required bank of tens, as hereinbefore described, and then advancing both disks 73 and 74 together unit by unit,

until the desired intermediate point is reached. At least one step of both disks together is always given. Thus to set the coinciding point at the thirty-fifth notch 5 from zero on the units disk or scale, the vernier disk 73 would first be advanced four steps (that is, three steps from zero) throwing the point of coincidence to the twenty-ninth notch from zero on the units disk, and 10 then both disks 73 and 74 would be stepped ahead together a distance of six units, and the notches of the three disks would then coincide at the thirty-fifth notch from zero on the units scale, and no coincidence would 15 occur in advance of that point. By this mechanism a stopping point may thus be established at a point far distant from the zero position, by relatively slight movements of the disks 73 and 74.

20 The disks 73 and 74 are provided with ratchets 83, 84, respectively, (see Fig. 5) with which the pawls 85 and 185 of a stepping magnet 86 are adapted to engage. The ratchet disk 83 is mounted upon the same 25 tubular shaft 106 (see Fig. 4) with the vernier disk 73, and similarly the ratchet disk 84 is mounted upon a concentric tubular shaft 107 which carries the vernier disk 74. The disks 73, 74 and their respective ratchets 30 are yieldingly held in their normal position by means of springs 108 and 109. Holding pawls 87, 88, shown most clearly in Figs. 2, 5 and 8, may be thrown into engagement with the ratchets 83, 84, respectively, to hold 35 the latter in the positions to which they may be advanced. These holding pawls 87 and 88 are normally held out of engagement with their ratchets by a stop-screw 110 carried by the armature lever 112 of the holding magnet 91. When said holding magnet 40 is excited the stop screw is withdrawn and the holding pawls permitted to engage their respective ratchets. The stepping pawl 85 is normally held out of engagement with 45 ratchet 83 by a stop-screw carried by armature lever 112 of holding magnet 91, but is released and permitted to engage said ratchet when the holding magnet is excited. The other stepping pawl 185 is normally held 50 out of engagement with ratchet 84 by an arm 113 of the armature lever 114 of a shift magnet 90, said pawl 185 being allowed to engage said ratchet 84 when the shift magnet is excited. Fig. 5 illustrates the relative 55 positions of the parts when the holding magnet 91 alone is excited, the armature of the shift magnet 90 being unattracted. If the pawl 85 alone is thrown into gear with its ratchet 83, the step magnet will only advance the vernier disk 73, the other disk 74 being unaffected; but if both stepping pawls 85 and 185 are thrown into engagement with the ratchets 83 and 84, the stepping magnet 60 will then advance both of the vernier disks

73 and 74 together. By virtue of this construction, it is unnecessary to have separate stepping magnets for long and short steps, as the single stepping magnet 86 can act first as a "long-step" magnet, to advance the vernier disk 73, giving the tens division, 65 and then after the operation of the shaft magnet 90, said step magnet may advance both disks 73 and 74 together to give the units divisions.

70 The holding magnet 91 has an armature 75 lever 112 which is adapted to bring into service the holding pawls for all the ratchets of the operating mechanism. As shown most clearly in Figs. 2 and 3 and in the diagram Fig. 1, the armature of the holding magnet 91 may also be arranged to operate a set of switch springs, and the units-wheel holding magnet 90 may also operate a set of switch springs. A third set of switch springs may be controlled by the 80 sheave or carrier-pulley 71, being held in one condition by a stud 82 on said pulley when the latter is in its zero position, and allowed to shift when the pulley removes said stud in leaving its normal position. 90 Another set of springs may be controlled by the ratchet disk 83, said springs being held in one position when the ratchet disk is normal, and allowed to shift when said ratchet disk leaves its normal position. 95 These various switch springs may be used as required to effect such circuit changes as may be desirable in the system with which the selector is to be used.

100 The operation of the mechanism will in general be as follows: The holding magnet 91 will first be energized to attract its armature, allowing the pawl 85 of the stepping magnet to engage the ratchet 83, and also bringing into service the holding pawls 87 and 88 of ratchets 83 and 84 and holding pawl 89 of the ratchet disk 76 which rotates with the carrier pulley or sheave 71. The step magnet may now, through the agency of the ratchet 83, advance the vernier 105 disk 73 the required number of steps to bring the point of coincidence of the notches on disks 73, 74 in the required bank of tens or long divisions of the scale. The shift magnet 90 will then be operated to bring 110 the stepping pawl 185 into engagement with ratchet 84, whereupon further actuation of the stepping magnet will advance both disks 73, 74 together the required number of 115 steps to reach the intermediate point or 120 "units place" desired, on the scale. The stop being thus set, the clutch magnet 70 is then excited, whereby the constantly-rotating shaft 72 is coupled to drive the carrier pulley 71 and raise the brush carrier 125 rod, at the same time advancing the pawl 75, carried by disk 76, around the periphery of the disks 73, 74 and 78. When this

pawl 75 reaches the predetermined point at which the notches in the three disks coincide, it drops in and moves disk 78 sufficiently to operate the clutch release springs 79 which may be arranged to open the circuit of the magnetic clutch in an obvious manner. The traveling brush of the selector has thus been moved to the required point and stopped. If a further movement of the brush is desired, as in hunting for an idle terminal, the stepping magnet may be given a stroke to advance the disk 73 and throw the notches now under the pawl 75 out of coincidence, whereupon the clutch 15 may be thrown on again by the recovery of springs 79, and rotate the carrier pulley to continue the travel of the selector brush until it reaches an idle terminal, whereupon the clutch magnet may be finally deenergized, leaving the traveling brush of the selector in contact with the idle terminal, which operation, however, since it forms no part of the invention as herein claimed need not be further described, the mechanism being held against return to normal by the holding pawls controlled by the holding magnet 91.

When the holding magnet 91 is deenergized, its armature in recovering will withdraw the various holding pawls from their ratchets, and allow the whole mechanism to return to normal position.

We wish to make reference here to a patent granted to James L. McQuarrie and Edward B. Craft, No. 949,836, dated February 22, 1910, in which many features of the present invention are disclosed but are not claimed specifically; that patent being directed more broadly toward the general features of a selector switch operated by power-driven mechanism under control of an electromagnetic stop-setting mechanism of any suitable type, while the present invention relates to the specific mechanism in which two or more controller parts are arranged to act in combination, on the principle of a vernier or a combination-lock, to set a stop which is determined by a relative adjustment of such parts (and in some cases by a further collective adjustment thereof with reference to other parts). It will be evident, however, that the particular form and nature of such controller-parts may be varied within wide limits without departing from the spirit of this invention.

We claim:—

1. In a selector switch controlling device, the combination with a plurality of relatively adjustable controller members, of a part having relative movement with respect to said controller members, and stop means brought into action by the mechanical cooperation of said relatively-movable part with said controller members jointly, according to their adjustment.

2. In a selector switch controlling mechanism the combination with a plurality of relatively adjustable controller parts, of selectively operated step-by-step mechanism for imparting such relative adjustment, and stop means controlled by the relative adjustment of said parts.

3. In a selector controlling mechanism, the combination with relatively-adjustable controlling members having scales of different length, of selective setting mechanism for causing relative adjustment of said parts to determine the coinciding point of said scales, an actuating member adapted to respond to a coincidence of said scales, and means for causing relative movement of said member with respect to said scales.

4. A selector switch controlling mechanism comprising relatively adjustable parts adapted to act in combination, electromagnetic selective mechanism for setting said controller parts in definite combination, a stop means, and means responsive to the combination of controller parts for actuating said stop means.

5. A selector switch controlling mechanism comprising relatively-adjustable stop-setting parts, a stop device, and means adapted to coöperate with said stop-setting parts jointly to actuate said stop device.

6. In a selector switch controlling mechanism, two or more relatively adjustable parts having scales with divisions of different lengths, a coöperating member adapted to respond to a coincidence of the scales upon said adjustable parts, and means for causing relative travel of said member with respect to said adjustable part.

7. A selector switch controlling mechanism comprising a stop, a plurality of stop setting parts, electromagnetic means for causing the relative adjustment of said stop setting parts, and means whereby the relative position of said stop setting parts determines the operative position of said stop.

8. In a switch controlling mechanism, a controlling device having relatively-adjustable juxtaposed parts having openings spaced apart to form differently-divided scales on the respective parts, means for causing relative adjustment of said parts to set the openings in coincidence at different points, and a rider adapted to travel with respect to said controller parts and arranged to actuate the device to be controlled, in entering said coinciding openings, whereby said device to be controlled is actuated according to the extent of travel of said rider, determined by the relative adjustment of said controller parts.

9. In a selector switch controlling mechanism, the combination with two rotatable controller disks concentrically mounted side by side, said disks having notches on their edges spaced apart at different intervals on

the respective disks, electromagnetic step-by-step mechanism responsive to selecting impulses for causing relative adjustment of said controller disks, a pawl adapted to travel around the edges of said disks, and stop means actuated by said pawl in engaging coinciding notches of said controller disks.

10. A selector switch controlling mechanism having a controlling part whose adjustment determines long divisions of advance of said switch; a second controlling part, the adjustment of both parts together determining short divisions of advance of said switch, a step magnet and shift mechanism adapted alternatively to cause one of said parts, or both parts together to be actuated by said step magnet.

11. A selector switch controlling mechanism having two controlling parts whose adjustment relatively to each other determines long divisions of advance of said switch, and whose collective adjustment determines short divisions of advance thereof, a step-magnet, ratchet mechanism operated thereby for advancing one of said parts independently, a shift-magnet and ratchet mechanism brought into action thereby for permitting said step-magnet to advance both parts in unison.

12. A selector switch controlling mechanism having two controlling parts and means governed jointly thereby according to the positions of said parts for determining the operation of said switch, an independent advance of one part serving to determine long divisions of advance of said switch and an advance of both parts together determining further short divisions of advance of said switch, a "stepping" electromagnet, step-by-step mechanism actuated thereby for advancing one of said controlling parts, a shift magnet, and step-by-step mechanism brought into action by said shift magnet to permit said stepping magnet to advance both controlling parts together.

13. In a switch controlling mechanism the combination with relatively-adjustable controller-disks arranged side by side, said disks being notched at intervals around their peripheries, the intervals between the notches being different upon the respective disks, a pawl, arranged to ride around the edges of

said disks, and to enter the first coinciding notches therein, a stop-disk arranged beside said controller disks and having notches adapted to be engaged by said pawl in entering coinciding notches at any point around said controller disks, and a stop-switch actuated by said stop-disk when the same is engaged by said pawl.

14. A selector switch controlling mechanism comprising a stopping switch a controlling device comprising relatively-adjustable juxtaposed parts having openings spaced apart to form differently-divided scales on the respective parts, electromagnetic selective mechanism for causing relative adjustment of said parts to set the openings thereof in coincidence at definite points, a rider arranged to travel along said juxtaposed controller parts and to enter said openings at the first point of coincidence thereof, and means actuated by said rider in entering such coinciding openings for operating said stopping switch.

15. In a selector switch controlling mechanism, the combination with a shaft, rotatable vernier controller wheels mounted side by side upon independent sleeves concentric with said shaft, said wheels having peripheral notches at differently-spaced intervals, a ratchet carried by each of said sleeves for operating the respective controller wheels, electromagnetic stepping mechanism for advancing one or both of said ratchets, a pawl moving with said shaft adapted to travel around the edges of said controller wheels and to enter the first coinciding notches, and a stop wheel mounted beside said controller wheels and having a toothed periphery adapted to be engaged by said pawl when the latter enters coinciding notches of said controller wheels, and stop means actuated by said stop-wheel when the latter is engaged by said pawl.

In witness whereof, we hereunto subscribe our names this thirtieth day of December A. D., 1907.

EDWARD B. CRAFT.
AMOS F. DIXON.
